AWNNG ARM ADJUSTMENT

Henry C. Heiser, Berea, Ohio, assignor to The
Astrup Company, Cleveland, Ohio, a corpora-
tion of Ohio

Application October 6, 1938, Serial No. 233,686

3 Claims. (Cl. 156—44)

The invention relates generally to folding awning arms and more particularly to adjustable spring tension means for holding the arms in unfolded position.

5 Certain prior awning arm constructions have been difficult to adjust, and it is usually necessary to readjust the amount of tension applied to the arms one or more times after they are installed, so that the time and difficulty incident to the adjusting operation is accordingly multiplied.

10 The most efficient and desirable location for applying the tension is at the joint between the inner and outer arms, and where flat bar arms are used a tension spring has been housed in an open-ended tube secured to one arm adjacent the joint between the arms and the tension adjusted by reaching into the tube.

Such a construction is not always satisfactory because the adjusting means preferably includes 20 screw threads to which moisture in the atmosphere has access through the housing tube; and where the arms themselves are tubular it is desirable to house the spring in one of the arms, in which case it is difficult as well as inconvenient 25 to provide access to the tension means inside the tubular arm.

Accordingly, it is an object of the present invention to provide improved tensioning means at the joint between a pair of folding awning arms, 30 which means is capable of rapid and easy adjustment before and after installation.

Another object is to provide an improved awning arm adjustment in which the tensioning means, including adjusting parts which may be 35 rendered inoperative by corrosion, is permanently incased in a closed housing.

A further object is to provide an improved awning arm adjustment in which the tensioning means is enclosed in a housing and easily ad- 40 justable from the exterior of said housing.

A still further object is to provide an improved awning arm adjustment particularly adapted for tubular arms and having the tensioning means enclosed in one of said arms.

45 And finally, it is an object of the present invention to provide an easily adjusted folding awning arm construction which is light in weight and inexpensive to manufacture, ship, install and maintain.

50 These and other objects are attained by the parts, elements, improvements, combinations and arrangements comprising the present invention which is disclosed by way of example in the accompanying drawing and described and claimed 55 herein.

In general terms the invention may be stated as including a spring located within one tubular arm or within a tubular housing on one arm, a connector rod having a nut abutting one end of the spring, and means swivelly connecting said 5 connector rod to the other arm whereby said rod may be turned to adjust said nut without disconnecting the rod from the other arm.

Referring to the drawing forming part hereof; Figure 1 is a side elevation of a folding awning 10 arm mounted in extended position on a support and equipped with the improved spring tension means;

Fig. 2 is an enlarged fragmentary view similar to Fig. 1, partly in section, to show the ten- 15 sioning means;

Fig. 3 is a plan view, partly in section, of the parts shown in Fig. 2, showing the arms in partially folded position;

Fig. 4 is a transverse sectional view as on line 20 4—4, Fig. 2; and

Fig. 5 is a transverse sectional view as on line 5—5, Fig. 3.

Like reference numerals refer to like parts throughout the several views in the drawing. 25

The folding awning arm indicated in Fig. 1 includes an inner arm 6 pivoted for lateral swinging on a wall bracket 7 in a usual manner, and the wall bracket is suitably secured to a support 8, as by bolts 9. Preferably adjusting means 30 indicated generally at 10 are provided on the wall bracket 7 for adjusting the arm vertically as desired.

A tubular arm 11 is hinged at its inner end to the outer end of inner arm 6 by means of a hinge pin indicated at 12, and the outer arm 11 is provided at its outer end with a fitting 13 adapted for mounting a front rod (not shown) to which the awning fabric is secured in a usual manner.

40 Preferably, the inner end of the outer arm 11 is provided with a hinge fitting 14 telescoped thereover and having an offset yoke 15, the ears 16 of which are journaled on the hinge pin 12. The inner tubular arm 6 has a hinge fitting 45 17 detachably secured on its outer end, and the fitting 17 is provided with ears 18 journaled on the hinge pin 12 and overlapping the ears 16.

The hinge fitting 17 is preferably provided with a tubular portion 19, which telescopes over the 50 inner end of the tubular arm 6 and has a shoulder 20 against which the end of the arm 6 abuts. Preferably, the tubular portion 19 is split as shown at 21, and ears 22 are provided at each side of the split through which a bolt or rivet 55

23 is inserted for clamping the tubular portion 19 around the tubular arm 6. Preferably, set screws 24 are screwed through the tubular portion 19 and into the arm 6 to prevent the arm 5 from turning or slipping in said tubular portion.

The improved tensioning means for urging the arms 6 and 11 toward unfolded position preferably includes a helical spring 25 located within the tubular arm 6. A connector rod 26 extends 10 through the spring 25, the end of said rod projecting out of the tubular portion 19 at the hinge end thereof and having an enlarged head 27 thereon preferably provided with circumferentially arranged sockets 27a. The other end of 15 the rod is screwed into a nut 28, which abuts the other end of the spring for compressing the same.

Preferably a spring abutment plate 29 is inserted through a slot 30 in the hinge end of the 20 tubular portion 19 for abutting the end of the spring opposite the nut 28. The plate 29 is provided with a slot 31 for fitting around the connector rod 26, so that the plate 29 may be inserted in position after the rod 26 and spring 25 are positioned in the tubular arm 6.

Preferably one end of the spring 25 is bent angularly in the direction of the longitudinal axis of the arm, as indicated at 32, and adapted to fit in a notch 33 in the nut 28 (Fig. 4). The other 30 end of the spring is provided with a similar angularly bent portion 34 for fitting in a hole 35 provided in the abutment plate 29. Thus, when the parts are assembled with opposite ends of the spring engaged in the nut and the abutment 35 plate 29, the nut is positively prevented from turning.

Means providing a linkage connection between the connector rod 26 and the arm 11 preferably includes a chain 36 connected at one end to a 40 swivel yoke 37 engaging behind the head 27 of connector rod 26. This swivel connection permits axial rotation of the rod 26 without turning the chain 36. The other end of chain 36 is preferably pivotally connected to an ear 38 projecting radially from a sleeve 39 which is journaled on the hinge pin 12 between ears 16 and provided with a projection 40 abutting the yoke 15. Thus, turning movement applied to sleeve 39 by a pull on the chain 36 is transmitted to the 50 arm 11 to cause it to rotate on the hinge pin.

In operation, the amount of spring tension urging the arms to unfolded position may be easily and quickly adjusted from outside of the tubular arms even though the spring 25, nut 28 55 and the major portion of connector rod 26 are completely housed within the arm 6. By inserting a pin or suitable tool in any of the sockets 27a of head 27, the rod 26 may be rotated axially to screw it into or out of the nut 28 and vary the 60 compression on the spring, the swivel yoke 37 permitting turning of the rod 26 relative to the chain 36.

It will be observed that the only parts subject to becoming inoperative due to corrosion are 65 the interengaging screw threads on the rod 26 and nut 28, and they are completely encased and protected from the weather at all times.

The improved spring tensioning means can be 70 assembled or disassembled in the tubular arm 6 from the hinge end of said arm. In assembling, the rod 26, with the nut 28 screwed thereon and the spring 25 encircling the rod, may be inserted into the arm 6 through its hinge end.

The spring abutment plate is then inserted in the slot 30 and the bent end 34 of the spring inserted in hole 35 of the plate.

If it is desired to disassemble the tensioning means, this may be done by inserting a tool 5 through slot 31 of plate 29 and compressing spring 25 sufficiently to disengage end 34 thereof from hole 35, after which plate 29 may be withdrawn and the spring and connector rod removed from arm 6.

Due to the ease of adjustment of the spring, the 10 spring tension can be relieved for shipping to such an extent that it is unnecessary to provide for locking the arms against unfolding during 15 shipment or transportation.

The amount of spring tension is easily adjusted after installation by an inexperienced person, so that the services of an experienced workman or special tools are not required.

While I have described the invention as applied 20 to a construction wherein both awning arms are tubular, the scope of the invention includes an awning arm construction having only one tubular arm, or a tubular portion on one arm for housing the tensioning means.

I claim:

1. In folding awning arm construction including inner and outer tubular arms hinged together, tensioning means urging the arms to unfolded position including a spring within one arm, an 30 abutment on said one arm engaging one end of said spring, a nut abutting the other end of said spring, a connector rod screwed into said nut and projecting out of said one arm, said spring being detachably secured at one end to said abutment and at the other end to said nut for holding 35 said nut against rotation, a linkage connected to the other arm, and means providing a swivel connection between the projecting end of said connector rod and the linkage.

2. In folding awning arm construction including inner and outer tubular arms hinged together, tensioning means urging the arms to unfolded position including a spring within one arm, a 40 spring abutment removably mounted at the hinge end of said one arm for abutting one end of said spring, a nut abutting the other end of said spring, one end of said spring being detachably secured to said abutment and the other end detachably secured to said nut, a connector rod 45 screwed into said nut and projecting out of the hinge end of said one arm, a linkage connected to the other arm, and a swivel yoke connecting the linkage to the projecting end of the connector rod.

3. In folding awning arm construction including inner and outer tubular arms hinged together, tensioning means urging the arms to unfolded position including a spring within one arm, a spring abutment removably mounted at the hinge end of said one arm for abutting one end of said spring and having a slot, a nut abutting the other end of said spring, one end of said spring being detachably secured to said abutment and the other end secured to said nut, a connector rod 55 screwed into said nut and projecting through the slot in the abutment out of the hinge end of said one arm, a linkage connected to the other arm, and a swivel yoke connecting the linkage to the projecting end of the connector rod.

HENRY C. HEISER.
